(57) **CLAIM**

The ornamental design for a makeup removal towel, as shown and described.

DESCRIPTION

FIG. 1 is a front, right side, top perspective view of the makeup removal towel showing my new design;

FIG. 2 is a rear, left side, bottom perspective view thereof; FIG. 3 is a front elevational view thereof.

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof showing how the towel would be hung from a support hook.

The broken lines shown in FIGS. 1-4 and 9 of the drawings depict stitching upon the makeup removal towel.

The broken lines shown in FIG. 9 of the drawings, illustrating a towel rack upon which the makeup removal towel can be hung, are for environment only and form no part of the claimed design.
